Primary Examiner—Catherine Tuttle(74) *Attorney, Agent, or Firm*—Fross Zelnick Lehrman & Sissu, P.C.; Charles T. J. Weigell, Esq.**CLAIM**

The ornamental design for a bottle, as shown and described.

DESCRIPTION

FIG. 1 is a front perspective view of a bottle showing my new design;

FIG. 2 is a front view of the bottle shown in FIG. 1;

FIG. 3 is a right side view of the bottle shown in FIG. 1;

FIG. 4 is a bottom view of the bottle shown in FIG. 1;

FIG. 5 is a rear view of the bottle shown in FIG. 1;

FIG. 6 is a left side view of the bottle shown in FIG. 1; and,
FIG. 7 is a top view of the bottle shown in FIG. 1.

The broken line showing of the internal compartment of the bottle is for illustrative purposes only and forms no part of the claimed design.
